ATTORNEY

UNITED STATES PATENT OFFICE.

EDWARD H. BAILEY, OF NEW YORK, N. Y.

RUG-HOLDER.

No. 833,571.

Specification of Letters Patent.

Patented Oct. 16, 1906.

Application filed March 1, 1906. Serial No. 303,609.

To all whom it may concern:

Be it known that I, EDWARD H. BAILEY, a citizen of the United States, residing in New York city, in the county of New York and State of New York, have invented certain new and useful Improvements in Rug-Holders, of which the following is a specification, reference being had to the accompanying drawings.

My invention relates to improvements in devices for retaining rugs, carpets, and like articles of floor-covering in adjusted position when placed loosely upon the floor and for retaining such articles in their original shape by preventing the curling of the edges, which so commonly occurs in these fabrics after long use.

The object of my invention is to provide a device of the class just described which will offer a maximum of resistance to accidental displacement and to the tendency on the part of the fabric to curl or otherwise lose its original shape with the minimum material and at a minimum cost and to provide such a device which will be cheap in manufacture, simple in construction, and efficient in operation.

My rug-holder is homogeneous in structure and is made of a single piece of rubber provided with an edging of fabric or other suitable material formed with needle-holes for the passage of the thread which binds the holder to the rug. By using the one material—rubber—homogeneity of structure is obtained, all cements are dispensed with and the life of the structure is lengthened, and a light, comparatively cheap, strong, stiff, and resilient holder results, having all the natural adhesiveness of rubber without the defects of the spring-steel rubber-coated combinations now on the market.

In order to distribute the material of the holder to the best advantage for the purposes in view, the holder is made in the form of an arrow, the head of which is provided at the point with a bulb which is in line with the shank, the latter extending diagonally back toward the center of the rug, while the arrow-head fits into the corner of the rug. Thus if the toe of a shoe worn by a person walking in the room should strike against the holder the blow would naturally be received by the bulbous point of the holder and by it transmitted in a direct line to the shank, which by reason of its long lever-arm would resist the tendency to displacement and restore the rug to its

original adjusted position. Further, the homogeneous nature of the material of which the shank of the holder is made and its stiffness combined with resiliency (it will be understood that the device is suitably vulcanized) all aid to make the device most efficient in operation.

By inserting an edging of fabric in the process of molding the holder means for firmly securing the holder to the rug are provided and the disadvantages of passing the thread through the rubber of the holder itself are avoided.

In the drawings illustrating the principle of my invention and the best mode now known to me of applying that principle, Figure 1 is a plan view of the bottom of a rug having attached to it rug-holders embodying my invention. Fig. 2 is a plan view of the floor side or face of my rug-holder; Fig. 3 is a modified form of what is shown in Fig. 2, and Fig. 4 is a plan view of the top or rug side of my rug-holder.

The body portion or head *a* is molded in one piece with the shank *b* and in the process of molding the edging *d*, of fabric or other suitable material, is inserted and becomes thoroughly embedded in the matrix of rubber, so as to be firmly secured to the molded holder, from the head of which it projects along the sides thereof. Through needle-holes *e*, formed in the edging *d*, a binding-thread is passed to secure the holder to the rug *f*, as illustrated in Fig. 1. By the provision of the edging *d* the thread does not have to be interposed between the floor-face of the rubber-holder and the floor, and thus is preserved all the natural adhesiveness of the rubber face. Further, the holder is much more expeditiously secured to the rug, and the thread is not liable to rot out, as when in contact with rubber.

The floor side of the holder is represented in Fig. 2, while a modified form thereof is shown in Fig. 3. In Fig. 2 the lower face of the holder is illustrated as provided with points *g*, projecting outwardly therefrom, and in Fig. 3 the squares or blocks *h* are substituted for the points *g*. These points *g* and blocks *h* sustain the pressure of the weight of the overlying material and adhere firmly to the floor, providing a frictional surface which resists blows tending to displace the rug and also overcomes any tendency of the fabric to slide along the floor.

The rug side or top of the holder, Fig. 4, is fluted, the lines *i j* being slightly raised above the surrounding level. These lines are shown in two sets, the lines of one set running in a different direction from the lines of the other set. The lines engage the rough under surface of the rug, carpet, or other fabric, and thereby overcome the tendency of the fabric to curl, creep, or otherwise change its original shape. On one side the holder adheres to the floor and on the other side closely to the rug.

The point of the head *a* is formed with an enlargement or bulb *c*, which lies directly in line with the shank *b*. This bulb *c* adds very materially to the stiffness and strength of the structure, both of which are cardinal points in these devices. The bulb *c* is naturally in a position to receive blows tending to displace the rug and transmits such blows to the shank *b* in a direct line, the shank *b* by its stiffness and resiliency, coupled with a long lever-arm, resisting the tendency to displacement and restoring the rug to its original adjusted position.

I am aware that metal devices of this class have been made with pads of soft rubber attached to them to give a frictional surface; but such devices do not possess the durability of my holder, as the rubber and metal frequently separate along the layer of cement used to join them, and the rubber is liable to crack and break off, due to the unequal bending of the metal and rubber. My holder is perfectly homogeneous in structure, being made up of one piece of molded rubber.

I am also aware that devices of this class are already upon the market in which a joint exists between the head or body portion and the shank member. In my holder the shank is integral with the body portion and weakness and lack of stiffness due to joints are avoided, while the required flexibility and

resiliency are obtained by the use of rubber as a material.

The piece of fabric which forms the edging *d* may extend throughout the holder from side to side thereof, thereby offering a large surface for the binding action of the rubber to act upon and serving to strengthen the structure as a whole.

As shown in the drawings, the fluting on the rug side of the holder (see Fig. 4) is very slightly raised above the edging *d*, and the latter and the fluted surface are brought into close contact with the under surface of the rug. On the other hand, (see Figs. 2 and 3,) the blocks or projections on the floor side of the holder extend a comparatively long distance from the edging *d* and serve to raise the rug some distance from the floor, thereby serving to prevent by their natural adhesiveness any sliding of the rug at the corners. The thickness of the body portion or coating below the fabric *d* is much greater than that of the body portion or coating above that fabric on the rug side of the holder, as will be readily seen by comparing either Fig. 2 or Fig. 3 with Fig. 4.

What I claim is—

1. A rug-holder made up of a single piece of rubber molded into shape and having a body portion and a shank extending from said body portion, and an edging of fabric molded with said body portion and projecting therefrom for attachment to the rug.

2. A rug-holder made up of a single piece of rubber molded into shape and having a body portion provided with corners and a shank extending from said body portion; one of said corners being formed with a bulbous enlargement in line with said shank.

EDWARD H. BAILEY.
